UNITED STATES PATENT OFFICE

ROY E. MCINTOSH, OF NEW YORK, N. Y., ASSIGNOR, BY MESNE ASSIGNMENTS, TO
J. EDWARD OGDEN COMPANY, OF NEW YORK, N. Y., A CORPORATION OF NEW
JERSEY

TOOL

Application filed September 27, 1926. Serial No. 138,104.

This invention relates to a tool for setting anchors.

It is well known that screw anchors are used for obtaining anchorage in walls of brick, stone, or cementitious material not adapted to directly receive a threaded element or bolt.

One type of anchor which is used for this purpose comprises an expansion member of 10 relatively soft metal mounted on an expanding member of relatively hard metal. In order to expand or set the anchor, the soft metal member or sleeve is tamped on the hard metal member and is forced outwardly 15 into firm gripping engagement with the wall opening. For an illustration of this type of anchor see Patent No. 1,164,903 to Ackerman et al., granted December 21, 1915.

When the hole for receiving the anchor 20 is drilled in a wall or other structure, considerable dust accumulates at the inner end of the hole and when the anchor is placed therein this dust tends to enter the inner end of the longitudinal opening in the anchor. This 25 dust impedes the travel of the bolt or threaded member that is inserted in the anchor after the anchor has been expanded.

This invention has for its salient object to provide a setting tool for an anchor of the 30 type specified so constructed that it will prevent dust from entering the threaded opening in the anchor when the anchor is positioned in a wall opening and expanded therein.

35 Further objects of the invention will appear from the following specification taken in connection with the drawings, which form a part of this application, and in which

Fig. 1 is a longitudinal sectional elevation 40 of one form of anchor in connection with which the tool is utilized;

Figs. 2 and 3 are end elevations of the two 45 ends of the anchor shown in Fig. 1;

Fig. 4 illustrates a slightly different form 50 of anchor in connection with which the tool is used;

Fig. 5 is a sectional elevation showing the 55 tool in connection with the anchors shown in Figs. 1 to 3 prior to the setting or expanding 60 of the anchor;

Fig. 6 is a view similar to Fig. 5 but showing the anchor expanded or set;

Fig. 7 is a transverse sectional elevation taken substantially on line 7—7 of Fig. 6;

Fig. 8 is a sectional elevation showing the 65 anchor shown in Fig. 6 in use for holding or supporting an article.

Fig. 9 is a sectional elevation similar to Fig. 6 but showing the tool in use with the anchor illustrated in Fig. 4;

Fig. 10 is a view similar to Fig. 8 but illustrating the anchor shown in Fig. 9; and

Fig. 11 is a sectional elevation showing another form of tool constructed in accordance with the invention in use in connection with 65 the anchor shown in Fig. 4.

The invention briefly described consists of a tool for use with anchors of the type specified and comprising a body portion which is adapted to engage the expansion member of 70 the anchor and a pilot or shank slidably carried by the tool and so dimensioned with reference to the anchor that it will extend into the inner portion of the longitudinal or threaded opening in the anchor. This pilot 75 acts as a guide for the body portion when the body portion is driven against the expansion member and also functions to prevent the dust accumulated at the end of the hole from entering the inner end of the longitudinal opening 80 in the anchor and thereafter impeding the passage of the threaded element, such as a bolt in the threaded opening in the anchor. Further details of the invention will appear from 85 the following description.

Figs. 1, 2 and 3 illustrate one form of anchor particularly adapted for expansion by the tool. This anchor comprises an inner expanding member 20 having an inner portion 21 provided with a tapered outer surface 22. The expansion member 20 is preferably formed of relatively hard metal and has a longitudinal opening therethrough, a portion 23 of the opening being threaded and the remaining portion 24 being substantially 90 cylindrical.

A expansible member 25, preferably formed of relatively soft metal, is mounted on the outer surface of the member 20 and has an opening formed therethrough. In the 95 100

form of the invention shown in Figs. 1 to 3, the inner end of this opening is tapered, as shown at 26, and the outer end has a ring 27 mounted therein. The inner diameter of the ring 27 is preferably as great as or slightly greater than the outer diameter of portion 28 of the expansion member 20, so that as the tool tamps the expansible member 25 inwardly in the hole the material of the expansible member will not be forced inwardly toward the axis of the anchor in a position to obstruct the outer end of the opening 23. This feature of the anchor is described and claimed in a copending application and need not be further described at this time.

Fig. 5 illustrates the anchor shown in Figs. 1 to 3 in use with a setting tool constructed in accordance with the invention. The tool comprises a body portion 30 having an opening 31 in which is slidably mounted a pilot or shank 32 having an enlarged portion or head 33 at the inner end thereof.

The pilot 32 is so dimensioned with respect to the anchor that it will be projected outwardly by the spring a sufficient distance to extend to the inner end 24 of the opening in the anchor.

Fig. 5 shows a wall or supporting structure 40 having a hole 41 bored therein, and it will be seen that dust 42 has accumulated at the inner end of the bore 41. The pilot 32 of the tool is first inserted in the anchor and is extended through the inner end thereof and the anchor and pilot are then inserted in the hole or bore, as shown in Fig. 5. The inner end of the pilot will press against the dust and will effectively prevent all but a negligible portion thereof from entering the inner end 24 of the opening through the anchor, thus permitting a variation in the bolt length and a variation in the depth of setting the anchor without detriment to the anchorage. It will be noted that the inner end of the expanding member 20 and the inner end of the pilot 32 are beveled and the beveling of these ends tends to force any dust laterally or radially away from the inner end 24 of the bore.

Force is then applied to the outer end of the body portion 30 of the tool as by blows from a hammer and the soft metal expansible member 25 is forced inwardly and radially, as shown in Fig. 6, into firm gripping engagement with the wall opening. During this operation the pilot 32 continues to be pressed into the inner end of the hole 41 and, therefore, continues to function to prevent dust from entering the inner end of the longitudinal opening of the anchor.

In Fig. 8 the anchor is shown in use and has threaded thereinto a bolt 45 which in turn is used to support a bracket or depending member 46. From the showing in Fig. 8 it will be seen that the bolt 45 can be threaded

into the inner end of the anchor without being impeded by dust.

Fig. 4 illustrates a slightly different form of anchor in which the opening 50 at the inner end of the expansion member 20 is flared. This flared opening does permit a small quantity of the dust at the inner end of the hole 41 to enter the flared opening 50. However, the pilot 32 of the tool still maintains a longitudinal opening through the anchor and the dust is packed tight around the pilot. When the tool and the pilot are withdrawn, a bolt 45 can be threaded into the anchor and will cut a thread in the packed dust as shown at 51 in Fig. 10.

Fig. 11 illustrates a slightly different form of tool in which the pilot 55 is threaded as shown at 56 for a portion of its length. The inner end 57 of the pilot is not threaded and a head 58 is formed on the opposite end of the pilot. The pilot is slidably mounted in an opening 59 formed in the body portion 30 of the tool, and a pin 60 extends through the head 58 of the pilot and into slots 61 formed in the opening 59. The pilot is, therefore, longitudinally slidable in the opening 59 but is non-rotatable therein.

The type of tool just described and shown in Fig. 11 is particularly adapted for positioning anchors a predetermined depth in the bore 41 in the wall or supporting structure. In order to accomplish this the pilot is threaded through the anchor a desired distance and the anchor and pilot are then placed in the hole. The distance from the inner end of the pilot to the inner end of the anchor will determine the distance from the bottom of the hole or inner end 41 to the anchor. When the anchor has been so positioned, force is exerted on the outer end of the body portion 30 of the tool and the expansible portion of the anchor is forced inwardly and laterally into firm gripping engagement with the wall opening 41. It will be evident that this form of tool can be used with the anchor of Figs. 1, 2 and 3, with like results.

From the foregoing specification it will be evident that a simple and practical tool for tamping or setting anchors has been provided and that the use of this tool will effectively prevent dust from entering the anchor and thereafter impeding the passage of a bolt or threaded element through the anchor.

Although certain specific embodiments of the invention have been particularly shown and described, it will be understood that the invention is capable of modification and that changes in the construction and in the arrangement of the various cooperating parts may be made without departing from the spirit or scope of the invention, as expressed in the following claims.

What I claim is:

1. A setting tool for an anchor compris-

- ing an expansion member of relatively soft metal, and an expanding member of relatively hard metal, said tool being adapted for tamping the soft metal member and having a body portion and a pilot or shank carried thereby and slidably relative thereto, said shank being mounted to extend at all times beyond the body portion a distance approximately as great as the length of the anchor.
2. A setting tool for an anchor comprising an expansion member of relatively soft metal, and an expanding member of relatively hard metal, said tool being adapted for tamping the soft metal member and having a body portion and a pilot or shank carried thereby and slidably relative thereto, said shank being mounted to extend at all times beyond the body portion a distance approximately as great as the length of the anchor, and a spring pressing said pilot outwardly relative to the body portion of the tool.
3. A setting tool for an anchor having a longitudinal opening therethrough and comprising an expansion member of relatively soft metal, and an expanding member of relatively hard metal, said tool being adapted for tamping the soft metal member, and said tool having a body portion adapted to engage and tamp the soft metal member and having a pilot adapted to extend at all times into the opening in said anchor and to the inner end thereof.
4. A setting tool for an anchor comprising an expansion member of relatively soft metal and an expanding member of relatively hard metal, said tool being adapted for tamping the soft metal member and having a body portion and a pilot or shank carried thereby and slidably relative thereto, said shank being mounted to extend at all times beyond the body portion a distance as great as the length of the anchor, and means for forcing said pilot to the inner end of the opening in the anchor.
5. A setting tool for an anchor comprising an elongated sleeve having an opening extending longitudinally therethrough and an expansible sleeve mounted on the outer surface of said elongated sleeve, said tool being adapted for expanding said outer sleeve on the inner sleeve and comprising a body portion with a surface adapted to engage the outer end of the expansible sleeve, and a pilot slidably carried by the body portion and so dimensioned as to extend at all times through the inner sleeve and to substantially fill the longitudinal opening in said sleeve.
6. A tool for tamping and setting anchors, said tool comprising a body portion and a threaded pilot slidably mounted in said body portion and projecting longitudinally therefrom at the inner end only thereof, and means for holding said pilot against rotation relative to said body portion.
7. A tool for tamping and setting anchors, said tool comprising a body portion and a pilot slidably mounted in said body portion and projecting longitudinally therefrom at the inner end only thereof, the projection portion of said pilot being threaded.
8. A setting tool for an anchor comprising an expanding member and an expansible member, said expanding member having a bore threaded for a portion of its length and enlarged at its inner end, said tool having a retractile extension adapted to extend prior to and during expansion of the anchor through the threaded portion of the bore and into the enlarged portion thereof.
9. A tool for setting an anchor comprising an expanding member and an expansible member, said expanding member having a bore threaded for a portion of its length and counterbored at its inner end, said tool having a retractile extension adapted to extend prior to and during expansion of the anchor through the threaded portion of the bore and into the counterbored portion thereof.
10. A tool for setting an anchor comprising an expanding member and an expansible member, said expanding member having a bore threaded for a portion of its length and countersunk at its inner end, said tool having a retractile extension adapted to extend prior to and during expansion of the anchor through the threaded portion of the bore and into the countersunk portion thereof.
11. A tool for setting an anchor comprising an expansion member of relatively soft metal and an expanding member of relatively hard metal, said tool being adapted for tamping the soft metal member and having a body portion and a pilot or shank carried thereby and slidably relative thereto, the shank being mounted to extend beyond the body portion into the expanding member, the inner ends of the expanding member and pilot being beveled.
12. A tool for setting an anchor comprising an expansion member of relatively soft metal and an expanding member of relatively hard metal, said tool being adapted for tamping the soft metal member and having a body portion and a pilot or shank carried thereby and slidably relative thereto, the shank being mounted to extend beyond the body portion into the expanding member, the inner ends of the expanding member and pilot being beveled at substantially the same angle to the axis.
13. A tool for setting an anchor comprising an expansion member of relatively soft metal and an expanding member of relatively hard metal, said tool being adapted for tamping the soft metal member and having a body portion and a pilot or shank carried thereby and slidably relative thereto, the shank being mounted to extend beyond the body portion

into the expanding member, the inner ends of the expanding member and pilot being beveled in such a manner as to form a conical inner end for the anchor and pilot.

6 In witness whereof, I have hereunto set my hand this 23 day of Sept., 1926.

ROY E. McINTOSH.
